TIGHT-LOOSE WRAP MECHANISM

Thormod Jensen, Laurelton, N. Y., assignor to
American Machine and Foundry Company, a
corporation of New Jersey

Application October 8, 1943, Serial No. 505,456

18 Claims. (Cl. 93—2)

This invention relates to wrapping machines, and especially to types of wrapping machines in which either a wrapper sheet or a wrapper in the form of an endless web is draped in the path of movement of an article onto a lifter table or conveyor, such that due to the movement of the article against the wrapper onto the lifter table the article is partially enwrapped with a portion of the wrapper or wrapper web extending unfolded relative to the article. In wrapping machines of this type it is especially desirable that the wrapper be properly disposed circumferentially about each article being wrapped and that the relative tightness or looseness of the wrapper can be controlled according to the desires of any particular manufacturer.

It is, therefore, an object of my invention to provide an improved device for controlling the feed of wrapping material either in wrapper sheet or endless web form so as to enable the attendant of the machine to so control the circumferential envelopment of a wrapper about an article that the package produced may be characterized as tightly wrapped, average wrapped or loosely wrapped.

The invention described hereinafter is of general application for wrapping machines, although it has particular reference to machines of the general type disclosed in Schmitt patent, No. 1,851,295, issued March 27, 1932, in which an article is forced against a draped wrapper web onto a lifter table and thence transported to folding instrumentalities.

It is a further object of my invention to provide mechanism for imparting to the conveyor or lifter table which transfers a partially wrapped article from an infeed station to a delivery station located generally above the infeed station an over-travel of the lifter table relative to the delivery station such that when taken in connection with wrapper controlling and holding mechanism the wrapper adjacent the front face of the article being wrapped is shifted upwardly relative thereto a predetermined amount, and the looseness of the wrapper about the article controlled thereby.

It is a further object of my invention to provide an improved mechanism for controlling the tightness of a wrapper encircling an article being wrapped, which article may be a loaf of bread or any other regular or irregular type of article.

While the invention is illustrated in connection with a bread wrapping machine, it is obvious

that its usefulness is not limited thereto and may be used with any type of wrapping machine.

Other objects of my invention will be set forth in the following description and drawings which illustrate preferred embodiments thereof, it being understood that the above statement of the objects of my invention is intended generally to explain the same without limiting it in any manner.

10 In the accompanying drawings which form a part of this specification, and wherein the several reference characters designate the same or like elements:

Figure 1 is a side elevation partly in section, 15 illustrating the novel tight-loose wrap mechanism in combination with a lifter table of a bread wrapping machine;

Figure 2 is a plan view of the same;

Figure 3 is an end elevation illustrating the 20 adjustable cam which controls the relative tightness of a wrapping about an article;

Figure 4 is a partial side elevation of the same taken on line 4—4 of Figure 3;

Figure 5 is also a partial side elevation of the 25 cam shown in Figure 3 taken on line 5—5 of Figure 3; and

Figures 6 to 10 are detailed side elevations illustrating the successive steps in creating a loose wrap.

30 In the embodiment selected for purposes of illustration, as shown in Figures 1 and 2, a lifter table 20, which may be of the general type disclosed in the above referred to Schmitt patent, is mounted for pivotal movement on a shaft 22 and is constrained to move between an article infeed position adjacent an infeed runway 24 and an article delivery position adjacent a delivery station and foldway 26 which is provided with the usual end folders and sealers 26a, 26b.

35 In the illustrated embodiment, lifter table 20 consists of a pivoted frame 28 which supports a plate 30. As mentioned hereinabove, frame 28 is swingably mounted on shaft 22 supported in side frames 32 of the wrapping machine. Lifter table 20 is operated in timed relation with the several functioning parts of the wrapping machine by means of an adjustable connecting rod 34 having one end connected at 35 to frame 28. The other end of the connecting rod 34 is connected to an arm 36 of a lever, loosely mounted on shaft 38 suitably supported in side frames 32. The other arm 40 of the lever is provided with a cam follower 42 tracking a cam 44 mounted on a cam shaft 46 supported by bearings (not shown)

45 in the side frames 32 and driven by means of a

suitable gear 48 (Figure 2) from the main drive shaft (not shown) of the wrapping machine.

Mechanism forming a part of the structure for effecting the desired degree of tightness of wrapping, viz., "tight wrap," "average wrap," or "loose wrap," as the case may be, is mounted on and supported by the lifter table 20. This mechanism may consist of a clamping plate 50 attached to an arm 52 loosely mounted on a shaft 54 held by lugs 56 formed on bracket 58 which is slidably supported by a pair of spaced studs 60, each secured to a bracket 62. Brackets 62 are mounted on the lower part of plate 30 of the lifter table, as shown in Figures 1, 2 and 6 to 10, inclusive. Bracket 58 is also equipped with a hub 64 provided with a bore through which projects a stud 65 having at one end a head 66 and at the other a forked lug 68. Connected to lug 68 by means of a pivot pin 69 is one end of an adjustable rod 70 having its other end connected to an arm 72 loosely mounted on a stud 74 fixed in a suitable hub on lifter table frame 28 (Figures 1 and 2). Pivot 76 connecting rod 70 and arm 72 mounts a manually operable hand lever 78 which is provided with a control lug or cam 80 adapted to engage a pin 82 carried by cam lever 84. By means of handle 79 the position of cam 80 can be controlled at the will of the operator for reasons described hereinafter.

Lever 84 loosely mounted on stud 74 carries a cam follower 86 which tracks a cam 88 loosely mounted on shaft 22. Cam 88 is provided with a hub 89 coupled to the hub 90 of a sprocket 91 which by means of a chain 92 is driven from sprocket 94 secured to cam shaft 46. A tension spring 96 having one end attached to arm 72 and the other end anchored to lifter table frame 28 assures constant contact of follower 86 with cam 88 and also provides a flexible coupling between cam lever 84 and control arm 72. A tension spring 67 encircling stud 65 insures a resilient coaction between plate 50 and clamping member 104 when the plate 50 is clamping the paper wrapper or web.

As a result of the mounting of hand lever 78 and the connections just described the action of cam lever 84 can be controlled merely by swinging hand lever 78 in the direction of the arrow (Figure 1) to vary the position of clamping plate 50 and thereby control its coaction with plate 104. This is because pin 82 which bears against cam 80 and spring 96 is stronger than spring 65 so that the connection just described insures that lever 78 will be maintained either in clamping position, as shown in Figure 1, or in non-clamping position, as shown in dotted lines in Figure 1, and the location of plate 50 controlled thereby. When lever 78 and plate 50 occupy the positions indicated in dotted lines in Figure 1, the tight-loose wrap mechanism is inoperative.

The operation of the improved mechanism for controlling the relative tightness or looseness of a wrapper may be described as follows: An article A, such as a loaf of bread to be wrapped, is pushed from the feed runway 24 by mechanism similar to that shown and described in the above referred to Schmitt patent onto the elevator or the lifter table 20 by means of pusher arm 100. In the preferred embodiment selected for purposes of illustration, the wrapper assumes the form of a continuous web or sheet fed from a source of supply (not shown) and draped in the path of an article to be wrapped downwardly between the lifter table 20 and infeed runway

(as shown in Figure 1) so that as article A is pushed against the draped web W the article is partially enwrapped in the draped wrapping material W and an additional quantity of wrapping material is pulled from the source of supply by the article as the lifter table 20 is raised to the delivery position adjacent the delivery end foldway 26. The movement of the lifter table 20 controls the amount of wrapping material pulled from the source of supply and also the tightness of the material encircled about the article during the table movement. In order to control the amount of relative tightness or looseness of a wrapper circumferentially with respect to an article being wrapped, mechanism is provided to move the lifter table 20 upwardly beyond the plane of the foldway 26 (Figure 6) and thereby pull off an additional amount of wrapping material. Clamping plate 50 is then actuated to hold a portion of the additional length of wrapper and the lifter table 20 is moved downwardly into the plane of the foldway 26, as shown in Figure 1.

Due to the fact that the downwardly extending portion of the wrapper is held against downward movement with the lifter table 20, the movement of the latter causes the portion L to be shifted generally upwardly and away from the article, such as shown in Figures 1, 7, 8 and 9, where wrapper portion L is spaced from the front face and top of the article. In order to effect this operation, hinged plate 50, which has been described hereinabove, carried by lifter table 20, coacts with plate 104 during the upward movement of table 20 and drags or slides over the material web W but before the lifter table moves down from its overriding position to the plane of the foldway, as described, plate 50 clamps the paper web against an elastic or resilient surface 102, such as sponge rubber, fixed to clamp 104 and causes the outward and upward loosening movement of each wrapper relative to the article. In order to prevent downward movement of the wrapper web W relative to the face of the article being wrapped, as the lifter table 20 travels downwardly into the plane of the foldway 26, plate 50 preferably is so shaped and mounted that it swings about pivot 54 and its operative clamping part thereby continuously clamps the web or wrapping as the lifter table moves to its aligned position with foldway 26 thereby maintaining the portion L in the form of a loop spaced from the article for producing a loosely wrapped package.

A bridge plate 108 is provided with a lug 109 (Figures 1 and 2) connected to an adjustable rod 150 in turn connected to cam lever 152 pivoted on a stud 154 mounted on one of the side frames 32. Cam lever 152 carries a follower 160 tracking cam 162 connected to lever 152 and frame 32 maintains follower 160 in tracking engagement with cam 162 and also urges roller 106 into coacting engagement with roller 110 on lifter table 30. A stop pin 158 on frame 32 may be provided to prevent excess movement of cam lever 152 (see Figure 1).

The web W is held by plate 50 clamped against rubber plate 102 until roller 106 is moved into coacting clamping relationship with roller 110 on table 30. While so held a lap roller 118, which may be constructed and operated in the same manner as described in the above referred to Schmitt patent, is moved downwardly by suitable mechanism (not shown) to pull a length of web 75 from the web supply and make the same available

for the next article to be wrapped. Following the operation of the lap roller 118, plate 50 is retracted to the position shown in Figure 9 where it serves as a shear plate for knife 120, which is also constructed and operated in the same manner as disclosed in the Schmitt patent; to cut the wrapper from web W (Figure 10). Clamp plate 50 is moved to its inoperative position by means of cam 88 and coacting lever 84, arm 12, rod 70 and bracket. Spring 114 on shaft 54 (Figure 2) causes arm 52 mounting plate 50 to swing upwardly away from plate 102 a distance governed by the position of an adjustable stop screw 116 (Figures 1 and 9).

Cam 162 is provided with a low portion 163 by means of which through lever 152 and spring 156 it maintains rollers 106, 110 in clamping engagement during the operation of lap roller 118 and knife 120. Cam 162 also has an intermediate high portion 165 which causes bridge plate 108 and roller 106 to swing a slight distance away from roller 110 after the cutting operation to release the cut end of the web. As the movement of a partially wrapped article and its wrapper from table 30 continues, rollers 106, 110 act as guide rollers, and have substantially no clamping action on the unfolded end of the wrapper passing therebetween upwardly against the bottom of the article as it moves onto bridge plate 108, along foldway 26 and between conventional folding and sealing members 26a, 26b to complete the wrapping operation. A high portion 167 swings bridge plate 108 into open position relative to roller 106. In this manner the excess wrapper is disposed loosely about an article and a loose wrapped package results.

In order to further control the degree of looseness of wrapping, the cam 44 effecting the movement of the lifter table 20, is provided with an adjustable cam portion 122 (Figures 1, 3, 4 and 5), by means of which the amount of "over-travel" of the lifter table and thereby the amount of additional wrapping material pulled is controlled. Cam portion 122 is loosely mounted on a stud 124 carried by the cam 44 and is equipped with a slot 126 (Figures 3 and 4) of suitable length which engages with an eccentric portion 128 of a stud 130 carrying a knob 132. Stud 130 is loosely supported by the cam 44 and has a threaded portion 134 which engages with a lock nut 136. By loosening the latter and turning knob 132 the cam portion 122 can be set in such a way as to be moved above the cam surface of cam 44 or to be flush with the same. Since this portion of the cam controls the "over-travel" of lifter table 20, looseness of any degree can be effected. In order to facilitate the setting of the machine, the hub of knob 132 is provided with an indicator finger 140 (Figure 5) which may be operated in conjunction with a scale 162 secured to cam 44.

In case a normal wrap is desired, cam 122 is moved so that its operative face is flush with the face of cam 44 thereby limiting movement of table 30 into the plane of guideway 26. The attendant can throw the hand lever 78 in the direction of the arrow in Figure 1, which due to a different position of pin 82 on control cam 80 causes plate 50 to remain in a "retracted" position as indicated in dotted lines 50a of Figure 1, with the result that the web W is not clamped during wrapping operation and the wrapper is pulled tightly around said article. In forming normal wrapped packages, rollers 106, 110 are operated to clamp the paper during the operation of the lap roller 118, and knife 120 coacts with

inactive plate 50 to cut a wrapper from web W, as explained hereinabove.

In forming tight wrapped packages, cam portion 122 is adjusted relative to cam 44 so that its active track is flush with the edge of cam 44, thereby preventing upward movement of table 30 beyond the plane of foldway 26. Plate 50 coacts with plate 102 to hold the depending wrapper web portion (Figure 8) tightly against the front face of the article being wrapped. The rollers 106, 110 clamp the wrapper during the operation of lap roller 118 and knife 120. Due to the movement of a partially wrapped article during the operation of the lap roller 118 and knife 120, the wrapper is applied tightly thereabout.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a wrapping machine having an infeed guideway, an article foldway located in a plane spaced from said guideway, an article conveyor movable between said guideway and said foldway, and means for moving an article from said guideway onto said conveyor against a wrapper positioned to receive said article to effect partial enwrapping of said article with an unfolded portion of said wrapper extending outwardly beyond said article, mechanism for moving said conveyor from said guideway to a position beyond the planar limits of said foldway, means for holding a portion of said wrapper extending beyond said article while said conveyor occupies said position, and means comprising a part of said mechanism for moving said conveyor into substantial alignment with said foldway for causing said wrapper to be loosely wrapped about said article.
2. In a wrapping machine having an infeed guideway, an article foldway located in a plane spaced from said guideway, an article conveyor movable between said guideway and said foldway, and means for moving an article from said guideway onto said conveyor against a wrapper positioned to receive said article to effect partial enwrapping of said article with an unfolded portion of said wrapper extending outwardly beyond said article, mechanism for moving said conveyor from said guideway to a position beyond the planar limits of said foldway, means for holding a portion of said wrapper extending beyond said article while said conveyor occupies said position, means comprising a part of said mechanism for moving said conveyor into substantial alignment with said foldway to effect a loose wrap of said wrapper about said article, and a device associated with said last-named means for controlling the degree of looseness of a wrapper about an article.
3. In a wrapping machine having an infeed guide, an article foldway positioned in a plane spaced from said guideway, an article conveyor provided with an article supporting surface movable between said guideway and said foldway, and means for moving an article from said guideway onto said surface against a wrapper positioned to receive said article to effect partial enwrapping of said article in said wrapper with a portion of the wrapper extending outwardly beyond said article, mechanism for moving said conveyor vertically from article receiving position adjacent said guideway and positioning said article sup-

porting surface beyond the planar limits of said foldway, means for holding a part of said projecting portion of said wrapper substantially vertical relative to one face of said article while said surface occupies said position, and means forming a part of said mechanism for moving said conveyor in a reverse direction while said wrapper is held, and positioning said surface in the plane of said foldway prior to the removal of said article from said surface onto said foldway for causing said wrapper to loosen relative to said article to control the tightness of said wrapper relative to said article.

5. In a wrapping machine having an infeed guide, an article foldway positioned in a plane spaced from said guideway, an article conveyor provided with an article supporting surface movable between said guideway and said foldway, and means for moving an article from said guideway onto said surface against a wrapper positioned to receive said article to effect partial enwrapping of said article in said wrapper with a portion of the wrapper extending outwardly beyond said article; mechanism for moving said conveyor vertically from article receiving position adjacent said guideway and positioning said article supporting surface beyond the planar limits of said foldway, means on said conveyor for holding a portion of said wrapper substantially vertical relative to one face of said article while said surface occupies said position, and means forming a part of said mechanism for moving said conveyor in a reverse direction and positioning said surface in the plane of said foldway prior to the removal of said article from said surface onto said foldway for causing said wrapper to become loosened relative to said article to control the tightness of said wrapper relative to said article.

6. In a wrapping machine having an infeed guide, an article foldway positioned in a plane spaced from said guideway, an article conveyor provided with an article supporting surface movable between said guideway and said foldway, and means for moving an article from said guideway onto said surface against a wrapper positioned to receive said article to effect partial enwrapping of said article in said wrapper with a portion of the wrapper extending outwardly beyond said article; mechanism for moving said conveyor vertically from article receiving position adjacent said guideway and positioning said article supporting surface beyond the planar limits of said foldway, a stationary wrapper guiding and clamping member, means on said conveyor coacting with said member for holding a portion of said wrapper substantially relative to one face of said article while said surface on said conveyor occupies said position, and means forming a part of said mechanism for moving said conveyor and positioning said surface in the plane of said foldway prior to the removal of said article from said surface onto said foldway for causing said wrapper to become loose relative to said article to control the tightness of said wrapper relative to said article.

7. In a wrapping machine having an infeed guide, an article foldway located in a plane spaced from said guideway, an article conveyor provided with an article supporting surface movable between said guideway and said foldway, and means for moving an article from said guideway onto said surface against a wrapper positioned to receive said article to effect partial enwrapping of said article in said wrapper with a portion of the wrapper extending outwardly beyond said ar-

5. ticle; mechanism for moving said conveyor vertically from article receiving position adjacent said guideway and positioning said article supporting surface beyond the planar limits of said foldway, and means for holding said projecting portion of said wrapper substantially vertical relative to one face of said article while said surface on said conveyor occupies said position, said mechanism comprising a cam operative to move said conveyor in a reverse direction to position said surface in substantial alignment with said foldway to cause said wrapper to bow relative to said face of said article while said wrapper is held by said means as a result of the reverse movement of said conveyor.

7. In a wrapping machine having an infeed guideway, an article foldway located in a plane spaced from said guideway, an article conveyor movable between said guideway and said foldway, and means for moving an article from said guideway onto said conveyor against a wrapper positioned to receive said article to effect partial enwrapping of said article with an unfolded portion of said wrapper extending outwardly beyond said article, mechanism for moving said conveyor from said guideway to a position beyond the planar limits of said foldway, means for holding a portion of said wrapper extending beyond said article while said conveyor occupies said position, means comprising a part of said mechanism for moving said conveyor to substantial alignment with said foldway for causing said wrapper to loosen relative to said article thereby provide a loose wrap, and means operative upon movement of said conveyor into substantial alignment with said foldway for clamping said bowed wrapper.

8. In a wrapping machine having an infeed guideway, an article foldway located in a plane spaced from said guideway, an article conveyor movable between said guideway and said foldway, and means for moving an article from said guideway onto said conveyor against a wrapper positioned to receive said article to effect partial enwrapping of said article with an unfolded portion of said wrapper extending outwardly beyond said article, mechanism for moving said conveyor from said guideway to a position beyond the planar limits of said foldway, means for holding a portion of said wrapper extending beyond said article while said conveyor occupies said position, means comprising a part of said mechanism for moving said conveyor into substantial alignment with said foldway for causing said wrapper to bow outwardly beyond said article to thereby provide a loose wrap, a clamp member carried by said conveyor, a coacting clamp member spaced from said first-named member, and means for moving said coacting member to engage and hold a portion of said bowed wrapper.

9. In a wrapping machine having an infeed guide, an article foldway located in a plane spaced from said guideway, an article conveyor provided with an article supporting surface movable between said guideway and said foldway, and means for moving an article from said guideway onto said surface against a wrapper positioned to receive said article to effect partial enwrapping of said article in said wrapper with a portion of the wrapper extending outwardly beyond said article; mechanism for moving said conveyor vertically from article receiving position adjacent said guideway and positioning said article supporting surface beyond the planar limits of said foldway, means for holding said projecting por-

tion of said wrapper substantially vertical relative to one face of said article while said surface on said conveyor occupies said position, said mechanism comprising a cam operative to move said conveyor in a reverse direction to position said surface in substantial alignment with said foldway to cause said wrapper to bow outwardly relative to said face of said article while said wrapper is held by said means as a result of the reverse movement of said conveyor, and adjustable means on said cam for controlling the limits of movement of said conveyor relative to said foldway.

10. In a wrapping machine having a lifter table movable between an article receiving and an article delivering station, a delivery guide located proximate said delivery station, and means for feeding articles in succession onto said table and against wrappers positioned in the path of movement of said articles to partially enwrap each article and leave a portion of the wrapper extending beyond the article, mechanism for moving said lifter table and partially enwrapped article to a position above and out of alignment with said delivery guide, a device for holding a portion of the outwardly extending wrapper, and means for effecting relative movement between said device and lifter table for feeding a portion of said extended wrapper vertically upward to loosen said wrapper relative to said article being wrapped.

11. In a wrapping machine having a lifter table movable between an article receiving and an article delivery station, a delivery guide located proximate said delivery station and means for feeding articles in succession onto said table and against wrappers positioned in the path of movement of said articles to partially enwrap each article and leave a portion of the wrapper extending beyond the article, mechanism for moving said lifter table and partially enwrapped article to a position above and out of alignment with said delivery guide, a device for holding a portion of the outwardly extending wrapper, means for effecting relative movement between said device and lifter table for feeding a portion of said extended wrapper vertically upward to loosen said wrapper relative to said article being wrapped, and adjustable means for limiting the movement of said table relative to said delivery guide, said adjustable means being constructed and arranged to govern the relative tightness of a wrapper about an article.

12. Tight-loose wrapper control mechanism for a wrapping machine having means for moving partially wrapped articles along a delivery guide, comprising a lifter table for lifting partially wrapped articles from an infeed guide to a delivery guide, said articles having an unfolded portion of a wrapper extending from an article, a wrapper clamping member located adjacent the path of movement of said table, a coacting clamping member carried by said table, and means for effecting relative vertical movement between said table and clamping member after said wrapper is clamped to effect vertical movement of said clamped portion of said wrapper relative to said article being wrapped and form a loosely wrapped article.

13. Tight-loose wrapper control mechanism for a wrapping machine having means for moving partially wrapped articles along a delivery guide, comprising a lifter table for lifting partially wrapped articles from an infeed guide to a delivery

guide, said articles having an unfolded portion of a wrapper extending from an article, a wrapper clamping member located adjacent the path of movement of said table, a coacting clamping member carried by said table, means for effecting relative movement between said clamped portion of said wrapper relative to said article being wrapped and form a loosely wrapped article, and means for incapacitating said clamping member when it is desired to form a tightly wrapped article.

14. Tight-loose wrapper control mechanism for a wrapping machine having means for moving partially wrapped articles along a delivery guide, comprising a lifter table for lifting partially wrapped articles from an infeed guide to a delivery guide, said articles having an unfolded portion of a wrapper extending from an article, a wrapper clamping member located adjacent the path of movement of said table, a coacting clamping member carried by said table, means for effecting relative vertical movement between said table and clamping members to effect vertical movement of said clamped portion of said wrapper relative to said article being wrapped, and means for controlling the operation of said clamping member on said table for varying the vertical displacement of said wrapper.

15. Tight-loose wrapper control mechanism for a wrapping machine having means for moving partially wrapped articles along a delivery guide comprising a lifter table for lifting partially wrapped articles from an infeed guide to a delivery guide, said articles having an unfolded portion of a wrapper extending from an article, a wrapper clamping member provided with a resilient clamping surface located adjacent the path of movement of said table, a coacting clamping member carried by said table, and means for effecting relative vertical movement between said table and clamping members after said wrapper is clamped to effect vertical movement of said clamped portion of said wrapper relative to said article being wrapped.

16. Tight-loose wrapper control mechanism for a wrapping machine having means for moving partially wrapped articles along a delivery guide comprising a lifter table for lifting partially wrapped articles from an infeed guide to a delivery guide, said articles having an unfolded portion of a wrapper extending from an article, a wrapper clamping member provided with a resilient clamping surface located adjacent the path of movement of said table, a coacting clamping member carried by said table, and mechanism for effecting relative movement between said table and clamping members to effect vertical movement of said clamped portion of said wrapper relative to said article being wrapped, said last-named mechanism including means for effecting swinging movement of said clamping member on said table while said portion of said wrapper is clamped.

17. Tight-loose wrapper control mechanism for a wrapping machine having means for moving partially wrapped articles along a delivery guide, comprising a lifter table for lifting partially wrapped articles from an infeed guide to a delivery guide, said articles having an unfolded portion of a wrapper extending from an article, a wrapper clamping member located adjacent the path of movement of said table, a coacting clamping member carried by said table, means for effecting relative vertical movement between said table and clamping members to effect vertical movement of said clamped portion of said wrapper

relative to said article being wrapped, wrapper gripping means, and means for operating said gripping means to hold said paper against return movement prior to movement of said partially wrapped article along said delivery guide.

18. Mechanism for use in a wrapping machine for controlling the degree of looseness of a wrapper encircling an article, comprising a wrapper folding and delivery guide, a lifter table for moving partially wrapped articles to said guide with a portion of a wrapper extending unfolded along one side of an article, wrapper clamping means

for holding said portion of said wrapper, means for effecting relative vertical movement between said table and clamping means to move said portion of said wrapper vertically to bow said wrapper relatively to said face of said article, means for controlling the amount of relative movement between said clamping means and table, and means for controlling the operation of said clamping means to govern the tension in said wrapper relative to the four sides of said article.

THORMOD JENSEN.
